UNITED STATES PATENT OFFICE.

WALTER SCHWERDTFEGER, OF STUTTGART-UNTERTURKHEIM, GERMANY, ASSIGNOR
TO DAIMLER-MOTOREN-GESELLSCHAFT, OF UNTERTÜRKHEIM, GERMANY, A COR-
PORATION OF GERMANY.

METHOD OF BRAKING INTERNAL-COMBUSTION MOTORS.

1,160,659.

Specification of Letters Patent. Patented Nov. 16, 1915.

Application filed July 31, 1915. Serial No. 42,994.

To all whom it may concern:

Be it known that I, WALTER SCHWERDTFEGER, subject of the Emperor of Germany, residing at 24 B. Panoramastrasse, Stuttgart-Untertürkheim, Germany, have invented certain new and useful Improvements in Methods of Braking Internal-Combustion Motors, of which the following is a specification.

10 This invention relates to a method of braking internal combustion motors of the two, four or six-stroke cycle type by aid of the motor itself.

15 According to the invention, in order to increase the braking effect, instead of the air contained in the cylinder, the fuel-air-mixture contained therein is compressed after ignition and is then expelled.

20 In the drawing affixed to this specification the method according to the present invention is illustrated diagrammatically as applied to a vertical four-stroke cycle motor. The spiral surrounding the crank circle is intended to diagrammatically indicate 25 the four strokes of the piston when my improved method is in operation.

First stroke.—The piston passes from the upper part of the cylinder to the outer dead center and draws in a mixture of fuel and 30 air.

Second stroke.—The suction period ends in the outer dead center or somewhat later, as usual. Shortly after it is ended the explosive mixture in the cylinder is ignited, 35 either by adjusting the ignition device provided for the normal service of the motor or by aid of a specially provided ignition device thrown in, whenever the motor is to be braked. According to the quantity of 40 mixture, which can be varied in order to regulate the braking power, an increase of pressure will take place within the cylinder. The piston ascending during this time thereby suffers a higher resistance than 45 with compressed air or non-ignited mixture, the resistance increasing, as the piston proceeds on its upward course, on account of the compressed gases being ignited. As soon as the piston has reached the inner

dead center, or has come near it, the exhaust 50 valve is opened, a special device such as a displaceable cam shaft or displaceable cams being required for this purpose, as the motion of the exhaust valve, during the braking period, differs from the normal motion 55 during the regular service of the motor as a power engine. As soon as the exhaust is opened the compressed gases escape and the pressure becomes normal.

Third stroke.—Preferably the exhaust remains 60 opened all through the third stroke, thus allowing a full equalization of the pressure in the cylinder to that of the air to take place.

Fourth stroke.—Also during the fourth 65 stroke, while the piston is passing from the outer to the inner dead center, the exhaust valve remains open, thus allowing the exhaust gases in the cylinder to be expelled. The exhaust valve remains open until the 70 suction period begins (first stroke).

The braking effect can be regulated, as 75 mentioned before, by varying the quantity of mixture admitted into the cylinder or else by varying the time or the extent of opening of the exhaust valve. Instead of the exhaust valve a special valve may be provided for expelling the compressed and ignited gases.

I claim:—

1. The method of braking internal combustion motors which consists in igniting the explosive mixture in the cylinder immediately after a suction stroke has been completed by the piston, permitting the compressed gases to escape from the cylinder at approximately the end of the compression stroke immediately following and continuing the escape of said gases during the entire next succeeding stroke of the piston.

2. The method of braking internal combustion motors which consists in igniting the explosive mixture in the cylinder immediately after a suction stroke has been completed by the piston, permitting the compressed gases to escape from the cylinder at approximately the end of the compression

stroke immediately following and continuing the escape of said gases during the next two succeeding strokes of the piston.

3. In an internal combustion motor, the combination of a cylinder, means for compressing an explosive mixture therein, means for igniting the mixture before compression

thereof and means for exhausting the explosion gases at approximately the end of the compression strokes and during succeeding strokes of the piston. 10

In testimony whereof I affix my signature.

WALTER SCHWERDTFEGER.
